C. B. COATES

SAFETY SWITCH MECHANISM

Filed May 20, 1924

UNITED STATES PATENT OFFICE.

CHARLES B. COATES, OF CLEVELAND, OHIO, ASSIGNOR TO CHICAGO PNEUMATIC TOOL COMPANY, OF NEW YORK, N. Y., A CORPORATION OF NEW JERSEY.

SAFETY SWITCH MECHANISM.

Application filed May 20, 1924. Serial No. 714,554.

To all whom it may concern:

Be it known that I, CHARLES B. COATES, a citizen of the United States of America, and resident of Cleveland, in the county of Cuyahoga and State of Ohio, have invented new and useful Improvements in Safety Switch Mechanism, of which the following is a specification.

This invention relates to locking controls for switches for electrical machines, particularly of the portable or hand tool type, although by no means confined thereto. It has particular adaptation to quick acting switches having a reciprocatory bar arranged to move independently of the controlling device and forming the main switch, and a reversing switch mounted in proximity to the main switch.

Heretofore it has been proposed to dispose the reversing switch on the main switch in such a manner that the controlling device of the latter will prevent movement of the reversing switch handle. But since the reciprocatory switch bar moves independently of the controlling device, it has been found to be possible and in fact to happen in operation that the operator would move the controlling device just far enough to permit the throwing of the reversing switch while the main switch bar still remained in the "on" position, thus burning out the motor or causing other serious damage.

Among the objects of the invention are to lock the reversing switch against movement when the main switch is "on", to provide simple means for this purpose readily applied to prior devices as well as easily embodied in new devices, and in general to improve devices of the class described in the interest of safety both to the operator and to the equipment with a consequent increase in production and a reduction of costs.

The invention comprises broadly a lock for the reversing switch controlled entirely by the plunger or bar of the main switch and not by the latter's controlling lever. More particularly it comprises a stop pin automatically projected into the path of the reversing switch lever when the main switch is "on" and maintained there until the main switch moves to its "off" position, whereupon the stop pin is automatically withdrawn to permit the reversing switch to be thrown.

In order to illustrate the invention, one

concrete embodiment thereof is shown in the accompanying drawings, in which:

Fig. 1 is a plan view;

Fig. 2 is a vertical sectional view on the line 2—2 of Fig. 1 showing the main switch in the "off" position;

Fig. 3 is a view similar to Fig. 2 showing the main switch in the "on" position;

Fig. 4 is a horizontal sectional view following the irregular line 4—4 of Fig. 2; and

Fig. 5 is a perspective view of the locking mechanism with associated parts of the switch shown in broken outline.

The embodiment of the invention chosen for the purpose of illustration is shown in its adaptation to a well known type of quick acting switch mechanism wherein the main switch is operated by a reciprocatory bar which moves independently of the movement of the controlling device or trigger. As shown, the switch has an elongate housing A adapted to form a handle for the drill or other portable electrical tool to which the switch is adapted to be attached at its enlarged end B. This enlarged end B houses the double poles C of the main switch, which poles are adapted to be bridged by the contact member D carried by the insulating block E which forms a transversely projecting head for the reciprocatory member or bar F which extends into housing A. Bar F has spaced latching slots G and G' which cooperate with fixed stops H and H' in housing A, reciprocatory movement of bar F being effected by a spring I which is pivoted at one end to the bar and at its opposite end near the top of the pivoted controlling member or trigger J. As trigger J is rocked on its pivot spring I tends to draw the bar F in the direction of this rocking movement, which tendency cannot become effective until one of the projections j or j' of the trigger contacts the bar to force the latter downwardly and out of latching engagement with one of the stops H or H', since the tendency of spring I is to lift bar F and maintain it in a latched condition. The use of a loading spring K for insuring quick return of the trigger J to the "off" position is optional.

Associated with the main switch is a reversing switch, the housing L of which in the present instance is secured to the enlarged head B of the main switch so that the

reversing switch control M, pivoted at m, swings across housing A, (see Fig. 1 where in both positions of the reversing control M are shown, one in full lines and the other in broken lines). Although reverse control M may be of such length as to have its movement blocked by main switch trigger J when the latter is in the "on" position (Fig. 3), it will be apparent that it is still possible to throw the reverse switch while the main switch is "on" by rocking trigger J partly toward the right or "off" position, since a partial movement of trigger J has no effect on reciprocating bar F, which is not unlatched for movement under the built-up tension of spring I until trigger J reaches the limit of its movement to the right and projection j' forces bar F downwardly to unlatch the same from stop H'.
To prevent the actuation of the reversing switch while the main switch is "on", as described above, locking mechanism entirely under the control of the reciprocating member F of the main switch and constituting the present invention is provided. This locking mechanism comprises a stop or pin 6 mounted for limited movement in a bushing 7 secured in a bore at the junction of the main switch housing A and its enlarged head B, said stop being adapted to be projected into the path of movement of the reversing control M. A spring 8 encircling the reduced stem 6' of pin 6 within bushing 7 tends to maintain the pin in its operative position to lock control M against movement. Stem 6' projects beyond the bushing into housing A in proximity to reciprocating member F and is provided with an enlarged head 9 which is engaged by a suitable member controlled by reciprocating bar F for retracting pin 6 to its inoperative position. This member preferably takes the form of a bell crank 10 generally U-shaped, the parallel sides 10^a and 10^b of which have aligned pivots secured in blocks 11 fastened within the housing A in any suitable manner, as by screw bolts 12. Thus the bell crank member 10 straddles bar F and its rounded elongate upper end 10^c is provided at one extremity with a slot 10^d receiving stem 6' above head 9 and at its other extremity with a roller 13 adapted to be contacted by the laterally projecting head E of bar F to rock the bell crank thereby causing the sides of the slot 10^d to bear upon pin head 9 and retract the same against the thrust of spring 8 to inoperative position when the main switch is thrown to the "off" position (Fig. 2). When the switch is thrown to the "on" position (Fig. 3), the pressure against roller 13 is relieved, whereupon spring F restores stop pin 6 to its operative or locking position and rocks bell crank 10 to the left until roller 13 rests upon bar F.
From the above it will be apparent that

the lock for reversing switches disclosed prevents accidental or intended throwing of the reversing switch while the main switch is "on," that this action of the locking mechanism is insured by placing the locking mechanism entirely under the control of the reciprocating member of the main switch, that the locking mechanism can be readily applied to quick acting switches of the type described now in use by the simple expedient of boring holes for the lock pin bushing 7 and the screw bolts 12 for the blocks 11 on which the bell crank 10 is mounted, and that the locking mechanism is simple, inexpensive to construct, reliable and positive in action. While but one specific form of locking mechanism has been herein disclosed, it is to be understood that the invention is not limited thereto but covers all changes and modifications within the scope of the appended claims.

I claim as my invention:

1. In combination, a main switch having a reciprocating member, a reversing switch associated with said main switch, and means controlled by said reciprocating member for locking said reversing switch against movement while the main switch is "on."

2. In combination, a main switch having a reciprocating member, and a controlling device, said member being arranged for movement independently of the movement of said device, a reversing switch associated with said main switch, and means controlled by said member for locking said reversing switch against movement when said main switch is "on."

3. The combination of a main switch and a reversing switch, locking means for said reversing switch in the form of a stop movable into the path of movement of the reversing switch control, means continuously urging said stop into locking position, and means operated by said main switch when in "off" position for counteracting said second named means.

4. In combination, a main switch having a reciprocating member, a reversing switch associated with said main switch, and a movable stop controlled by said reciprocating member and arranged to lock said reversing switch when the main switch is "on."

5. In combination, a main switch having a reciprocating member, a reversing switch associated with said main switch, means for locking said reversing switch against movement, and means controlled by said member for rendering said locking means ineffective.

6. In combination, a main switch having a reciprocating member, a reversing switch associated with said main switch, a stop for locking said reversing switch against movement, and means controlled by said member for moving said stop out of locking position.

7. In combination, a main switch having a reciprocatory member, a reversing switch associated with said main switch, a movable stop for locking the reversing switch, means for moving said stop into locking position, and means controlled by said reciprocatory member for counteracting said first-named means.
8. In combination, a main switch having a reciprocatory member, a reversing switch associated with said main switch, a movable stop for locking the reversing switch, means for moving said stop into locking position, and a pivoted member engaged by said reciprocatory member for counteracting said first-named means.
9. The combination of a main switch and a reversing switch, a spring-pressed stop pin for locking the reversing switch, and means operated by the main switch when in the "off" position for moving said pin to inoperative position.
10. In combination, a main switch having a reciprocatory member provided with a lateral projection, a reversing switch adjacent said main switch, a movable stop for locking said reversing switch, and means engaged by the projection on said reciprocatory member for moving said stop to inoperative position.
11. In combination, a housing, a main switch therein having a reciprocatory member, a reversing switch associated with said main switch and having a control lever pivoted for swinging movement across said housing, and a stop pin under control of said reciprocatory member movable into the path of movement of said reversing lever to lock the same against movement.
12. In combination, a housing, a main switch therein having a reciprocatory member, a reversing switch associated with said main switch and having a control lever pivoted for swinging movement across said housing, a stop pin movably mounted in said housing and arranged to project into the path of movement of said reversing lever to lock the same against movement, and means controlled by said reciprocatory member for holding said pin in inoperative position when the main switch is "off".
13. In combination, a housing, a main switch therein having a reciprocatory member, a reversing switch associated with said main switch and having a control lever pivoted for swinging movement across said housing, a spring pressed stop pin mounted in said housing for locking said reversing lever against movement, and a lever engaged by said reciprocatory member when the main switch is "off" for holding said pin in inoperative position.
14. In combination, a housing, a main switch therein having a reciprocatory member, a reversing switch associated with said
- main switch and having a control lever pivoted for swinging movement across said housing, a spring pressed stop pin mounted in said housing for locking said reversing lever against movement, said pin projecting within said housing adjacent said reciprocatory member and means engaged by said member for moving said pin to release said lever.
15. In combination, a housing, a main switch therein having a reciprocatory member, a reversing switch associated with said main switch and having a control lever pivoted for swinging movement across said housing, a spring pressed stop pin mounted in said housing for locking said reversing lever against movement, and a bell-crank pivoted within said housing and arranged to engage said pin, said bell-crank being engaged by said member in the "off" position of said main switch to move said pin to inoperative position.
16. In combination, a housing, a main switch therein having a reciprocatory member, a reversing switch associated with said main switch and having a control lever pivoted for swinging movement across said housing, a spring pressed stop pin mounted in said housing for locking said reversing lever against movement, said pin having a head extending within said housing above said reciprocatory member, a bell crank comprising an inverted U-shaped member straddling said reciprocatory member and pivoted at its lower end to said housing, said bell crank receiving the stem of said pin above said head through a slot and arranged to be engaged by said reciprocatory member when the main switch is "off" to move said pin to inoperative position.
17. In combination, a housing, a main switch therein having a reciprocatory member provided with a transverse projection, a reversing switch on said housing having a control lever pivoted for swinging movement across the latter, a spring pressed stop pin mounted in said housing and normally disposed in the path of movement of said reversing lever, said pin having a head extending within said housing above said reciprocatory member, a bell crank comprising an inverted U-shaped member straddling said reciprocatory member and pivoted at the lower ends of its parallel sides to said housing, the rounded elongate upper end of said bell-crank having at one extremity a slot receiving the stem of said pin above said head and at its other extremity a roller for engagement with said projection on said reciprocatory member whereby said bell crank is rocked to bear upon said pin head to retract said pin to inoperative position.

Signed by me at Cleveland, Ohio, this 15th day of May 1924.

CHARLES B. COATES.
